115 VOLT ULTRA-VIOLET LAMP

John W. Marden, East Orange, N. J., assignor to
Westinghouse Lamp Company, a corporation of
Pennsylvania

Application April 21, 1932, Serial No. 606,554

11 Claims. (Cl. 176—1)

This invention relates to an ultra-violet lamp and relates more particularly to a lamp wherein a source of ultra-violet radiations and a source of illumination are combined in a unitary structure.

It is an object of the present invention to provide a combined ultra-violet and illuminative lamp for use on commercial line voltages.

Another object of the invention is to provide a source of illumination and a source of ultra-violet light in a common envelope and wherein the separate sources cooperate with each other to accomplish the result desired.

Other objects and advantages of the invention will be apparent from the following description together with the accompanying drawings in which:

Fig. 1 is a side elevational view of a device constructed in accordance with the present invention, the bulb and portions of the structure being broken away;

Fig. 2 is an enlarged detailed view showing a portion of the bulb shown in Fig. 1 partly in cross section;

Fig. 3 is a side elevational view of a modified form of the device with the bulb broken away to show the internal structure;

Fig. 4 is an enlarged detailed view of a portion of the bulb and structure shown in Fig. 3;

Fig. 5 is a side elevational view of another modification of the present construction with the bulb broken away to show the internal elements; and

Fig. 6 is a view similar to Fig. 5 but showing a modification of the elements for producing a glow discharge.

Inasmuch as the usual commercial line voltage is about 115 volts the following description of the selected practical embodiment of the invention is considered as when used on such voltage. It is to be understood, however, that the device may be so constructed and proportioned as to be operable on other voltages either greater or less to meet different conditions.

The invention may comprise a sealed container such as a glass lamp bulb having the usual screw base for connection to a source of electrical energy. As distinguished from the ordinary incandescent lamp bulb, however, the present container may comprise a relatively large chamber and a relatively small chamber. These chambers may be in communication and separated by a baffle or by a dividing wall.

The relatively large chamber may contain a tungsten filament which may be termed the illuminant and in the smaller chamber may be

disposed a pair of electrodes, a heater filament and a quantity of mercury.

As more clearly shown in Figs. 1 and 2 of the drawings, a practical example of the one form of the invention may comprise a bulb 18 having a screw base 11 and a flare tube 12 sealed to the bulb neck at 13. The usual exhaust tube 14 may be provided and lead wires 15 and 16 may extend through a press 17 and connect with the base in the usual manner. The bulb 18 may comprise a relatively large chamber 18 and a relatively small chamber 19. The lead wire 16 may extend from the press 17 and into the chamber 18 and a disk 21 of mica or other suitable material may be disposed in the orifice 22 between chambers 18 15 and 19.

The disk may be provided with an eyelet 23 through which the lead 16 extends and the lead may be bent at 24 to provide a shoulder to support the disk. The lead wire 15 may have an end 25 extended from the press 17 and one end of a coiled filament 26 may be secured to the said lead end. The opposite end of the filament may be connected to a conductor 27 which extends through an eyelet 28 in the disk 21 and may be bent at 29 to provide a construction symmetrical with the lead 16. For the purpose of insulating the lead 16 from the filament 26 when their space relation is close, the said lead is provided with a sleeve 31 preferably of glass and support members 32 may be secured to the sleeve and may extend therefrom to retain the filament from excessive movement when the lamp is subjected to impact.

The lead wire 16 and the conductor 27 extend into the chamber 18 and their free ends 33 and 34 are spaced a suitable distance apart and are provided with electrodes 35 and 36. The electrodes may consist of tungsten points or beads at the ends of arms and each arm is electrically connected with one end of a filament or heater element 37 so arranged as to be in close proximity to a pool of mercury 38 at the bottom of the chamber 18.

When constructing a device as above described, the bulb 18 may be of the same proportions as used for a 200 watt filament lamp. The glass of the bulb may be of such character as to transmit ultra-violet light. When constructing the device for 2 amperes the chamber 18 may have a volume of 1.2 cubic inches and if cylindrical as shown should be about 1 to $1\frac{1}{4}$ diameter depending on the length of the chamber. The disk or baffle 21 does not tightly fit the orifice so that communication is had between the chambers and if

mercury vapor enters the chamber 18 it will be condensed, by reason of the relatively cool chamber 18, and flow back into the chamber 18.

The filament 26 may operate at 100 volts with 5 two amperes of current. This filament serves as an illuminant and as a ballast resistance for the arc discharge between the electrodes 35 and 36. The beads or points of the electrodes may be cylindrical and should be about 50 mils long and 10 about 18 mils in diameter. The filament or heater 37 will give sufficient heat while drawing current at 30 to 60 volts to start an arc, the filament 37 being heated sufficiently to give good electrical emission.

15 An appreciable amount of mercury may be placed in the chamber 19; for example, an amount may be supplied sufficient to leave from one to three cubic millimeters of mercury after sealing off. The chamber 18 may contain an inert gas 20 such as argon, neon or helium at a substantial pressure say of about 10 cm.

When the device is operated, the filament 37 is heated and radiates heat to raise the temperature of the mercury pool producing vapor at a pressure 25 sufficient to support an arc between the electrodes 35 and 36 which is started by ionization due to the electron emission of the filament 37. Since the chamber 18 is large with respect to the chamber 19 and the temperature of the large chamber 30 is appreciably lower than the temperature of the small chamber 19 that the mercury vapor pressure in the large chamber does not become high enough to permit an arc or glow discharge to take place in the presence of the argon at the 35 pressure used.

When an arc starts, the voltage between electrodes 35 and 36 drops to about 15 volts so that the voltage across the filament 26 becomes 100 volts at which voltage it may operate at a temperature consistent with good life of the tungsten 40 filament.

The filament 26 which serves as a ballast to steady the arc gives a small amount of ultra-violet light, the arc, however, under good working conditions, gives about five times as much vital region ultra-violet radiations as found to be possible with a two hundred watt tungsten filament in a Corex bulb.

It is well known that a tungsten filament if run 50 at the proper temperature in a bulb previous to ultra-violet radiations will give an appreciable amount of such radiations. The filament employed, however, consumes such an amount of energy as to make the cost of operation relatively 55 costly compared to the amount of ultra-violet light produced. The present device which has a relatively low operation cost gives a relatively large amount of ultra-violent light and at the same time serves for general illumination.

60 The present lamp can be operated without an arc forming between the leads in the large chamber; first, because the pressure of mercury is too low; second, the leads are spaced a relatively great distance apart; and third, the argon pressure when used at a pressure of about 10 cm. tends to prevent arcing.

Although the above described construction shown in Figs. 1 and 2 provides an efficient and practical device, the same may be modified as 70 illustrated in Figs. 3 and 4 wherein the bulb 18 is provided with compartments 18 and 19 and lead-in conductors 41 and 42 which extend through the press 17. Within the compartment or pocket 19, are disposed a pair of electrodes 75 43 and 44. These electrodes are in the form of

a relatively large helical coil and ends thereof are connected with terminal conductors 45 and 46.

The opposite ends of the electrodes connect with the ends of a heater element 47 supported by a hook member 48 secured to a spud 49 extending 5 from an arbor 51 integral with the press 17. The spud 49 serves to support an insulative disk 52 preferably of mica; ears 53 being provided on the spud to hold the disk in place in the orifice 54 to substantially close the entrance between 10 the compartments 18 and 19. The terminal conductors 45 and 46 extend through the disk 52 and are secured to arms 55 and 56 which extend from an enlargement 57 on the arbor 51. Terminals of filaments 58 and 59 are secured to the 15 terminal conductors 45 and 46 and the opposite terminals of the said filaments are connected to conductors 41 and 42. The container 18 may be filled with an inert gas such as argon at a pressure 20 10 cm. and a quantity of mercury 51 may 25 be provided in the chamber 18. With the construction shown in Figs. 3 and 4, the operating current of the lamp serves to elevate the temperature of the filament or heater element 47 25 sufficiently to vaporize the mercury 51 and promote a discharge between the electrodes 43 and 44. When such discharge occurs which is in the form of an arc, the voltage drops between the electrodes.

While the filaments 58 and 59 operate at a 30 voltage sufficient to render them incandescent and capable of serving as an illuminant they also serve as a ballast resistance for the arc discharge.

In the constructions above described, the relatively large chamber was divided from the relatively small chamber by a disk which served to confine the heat within the small chamber but wherein the chambers by reason of the space between the disk and the wall of the container were in communication. In such a construction, the 40 vaporized mercury which escaped into the larger chamber would, by reason of the lower temperature of the large chamber, be condensed and flow back into the small chamber.

In the construction shown in Figs. 5 and 6 the 45 large and small chambers are hermetically sealed from each other. The light giving filaments, however, are in the same operative relation to the arc producing elements and serve as a ballast resistance therefor. In Fig. 5 the bulb 18 includes 50 a relatively large chamber 18 and a relatively small chamber 19. The small chamber 19 is provided with a press 62 through which conductors 63 and 64 extend. The lower ends of the said conductors terminate in the chamber 19 and are 55 connected with electrodes 65 and 66 respectively.

A heater element 67 in the form of a tungsten coil is provided with its terminals connected to the electrodes 65 and 66 and a quantity of mercury 68 is disposed in the lower end of the chamber 18 inasmuch as the chamber 19 is hermetically sealed from the chamber 18, the said chamber 19 may be exhausted by a tubulating operation at 69. Within the chamber 18 are disposed a pair of light giving elements in the form of helical coils 65 71 and 72 having ends connected to conductors 63 and 64 respectively. The opposite ends of the coils are connected with lead wires 73 and 74. A device constructed in accordance with the showing in Fig. 5 operates the same as the devices 70 previously described and the compartment 18 may be filled with a suitable inert gas or may be evacuated.

Fig. 6 is substantially the same as the construction shown in Fig. 5 but instead of the arc pro- 75

ducing electrodes, a pair of uni-potential cathodes 75 and 76 are provided. These cathodes, which may be termed cathode assemblies, are of similar construction and may each include a sleeve 5 77 having thereon an electron emissive coating 78.

Within the sleeves are disposed heater elements 79 having terminals connected with conductors 81 and 82 extending through the press 62. The sleeves 77 are electrically connected to the conductors 81 and 82 and opposite ends of the heater elements are secured to a conductor 83 which is supported by member 84 extending from the press 62. Thus, the heater elements are connected in series. Within the chamber 18 are disposed coil filaments 85 and 86 having ends connected with the conductors 81 and 82 and other ends connected with lead-in conductors 87 and 88 extending through press 17. The filaments 85 and 86 are thus connected in series with the 20 cathode assemblies 75 and 76.

Within the chamber 19 is a quantity of mercury 89 which, when the device is operated, becomes vaporized so that the impressed voltage between the indirectly heated surfaces of the 25 thermionically active cathodes emit electrons to ionize the vapor or gas within the chamber and produce a glow discharge. Ordinarily, such discharge would be unstable by reason of the voltage drop, the filaments 85 and 86, however, serve as 30 a current limiting or stabilizing means making the device a practical combination illuminating and ultra-violet lamp.

The construction shown as the glow discharge portion of the device illustrated in Fig. 6 is substantially the same as shown in co-pending application Serial No. 437,459 filed March 21, 1930 and assigned to the same assignee as is the present invention.

It is to be understood that in constructing 40 lamps in accordance with the present invention that the entire container may be of a glass which is permeable to ultra-violet emanating from the incandescent filaments in the large container in addition to the ultra-violet produced by the glow 45 or arc discharge. On the other hand, it is contemplated to make only the relatively small container or pocket of a glass such as Corex or the like which passes ultra-violet rays in which case the lower portion of the container may be united 50 to the upper portion by suitable means such as a graded seal well known in the lamp making art. It will be noted that in the construction shown in Figs. 1 and 2 a single filament is employed disposed adjacent to the insulative lead to avoid 55 any discharge occurring therebetween. In Figs. 3 and 4, however, two filaments are employed and so spaced that the possibility of a discharge is removed particularly in view of the environment employed.

60 A device constructed in accordance with the present invention provides an effective and economic means of producing ultra-violet light with artificial lighting and at the same time such a lamp used at ten feet should give eight-hour-a-day users from one to two erythema quantities of 65 ultra-violet per week.

Although a preferred embodiment of the invention is shown and described herein, it is to be understood that modifications may be made there- 70 in without departing from the spirit and scope of the invention as set forth in the appended claims.

What is claimed is:

1. An electric discharge device comprising a sealed envelope having a relatively large compartment and a relatively small compartment in

communication, a pair of electrodes in said small compartment, terminal conductors for said electrodes, a heater element bridging said electrodes, a quantity of mercury disposed in said small compartment for vaporization when heated by 5 said element to promote a glow discharge between said electrodes, and means substantially closing one compartment from the other to restrict the glow to said small compartment.

2. An electric discharge device comprising a 10 sealed envelope having a relatively large compartment and a relatively small compartment in communication, a pair of electrodes in said small compartment, terminal conductors for said electrodes, a heater element bridging said electrodes, 15 a quantity of mercury disposed in said small compartment for vaporization when heated by said element to promote a discharge between said electrodes, means for partially closing one compartment from the other for restricting the dis- 20 charge to said small compartment and means in said large compartment for stabilizing said discharge.

3. An electric discharge device comprising a 25 sealed envelope having a relatively large compartment and a relatively small compartment in communication, a pair of electrodes in said small compartment, terminal conductors for said electrodes, a heater element bridging said electrodes, 30 a quantity of mercury disposed in said small compartment to promote a glow discharge between said electrodes, a partition partially closing one compartment from the other for restricting the glow to said small compartment, an incandescent filament in said large compartment 35 and means connecting said filament to one of said terminal conductors.

4. A combined ultra-violet and illuminating device comprising a sealed container having a pocket, a pair of electrodes in said pocket, said 40 container and pocket being connected by a constricted opening, a quantity of mercury in said pocket, a heater element having its terminals connected to said electrodes and disposed to vaporize said mercury to produce a glow dis- 45 charge between said electrodes, a light source in said container and an inert gaseous environment in said container at a pressure appreciably greater than the pressure of the mercury vapor sufficient to support said glow discharge. 50

5. A combined ultra-violet and illuminating device comprising a sealed container having a pocket connected thereto by a passageway, a pair of electrodes in said pocket, means for sub- 55 stantially closing said passageway, a quantity of mercury in said pocket, a heater element having its terminals connected to said electrodes and disposed to vaporize said mercury to produce a glow discharge between said electrodes, a light source in said container and an inert gaseous 60 environment at a pressure appreciably greater than the pressure of the mercury vapor sufficient to support said discharge and means in said container for stabilizing said discharge.

6. A combined ultra-violet and illuminating 65 device comprising a sealed container having a pocket, a communicating passage between said container and pocket, a pair of electrodes in said pocket, a quantity of mercury in said pocket, a heater element having its terminals connected 70 to said electrodes and disposed to vaporize said mercury to produce a glow discharge between said electrodes, a partition substantially closing said passage, a light source in said container and an inert gaseous environment at a pressure 75

- appreciably greater than the pressure of the mercury vapor sufficient to support said discharge and an incandescent filament in said container in series with said electrodes to stabilize said discharge and give visible light.
5. An electric discharge lamp comprising a sealed envelope having a relatively large compartment and a relatively small compartment in communication by means of a constricted passage, tungsten electrodes in said small compartment, terminal conductors for said electrodes, a vaporizable material in said small compartment to impart illumination to the discharge between the electrodes, an incandescent filament in said large compartment and a gaseous environment inert with respect to said filament and electrodes and at a pressure appreciably higher than the vapor of said vaporizable material whereby the said vapor is substantially confined in said small compartment.
10. An electric discharge lamp comprising a sealed envelope having a gas chamber and a vapor chamber in communication, means providing an opening of a predetermined area between said chambers, electrodes disposed in spaced relation in said vapor chamber, terminal conductors for said electrodes, an amount of mercury in said vapor chamber, a heater element connected to said conductors to vaporize said mercury at the operating temperature of the device to initiate a discharge between said electrodes and means in said gas chamber for stabilizing said discharge.
15. An electric discharge lamp comprising a sealed envelope having a gas chamber and a vapor chamber in communication, a partition between said chambers so proportioned as to provide an opening of a predetermined area, electrodes disposed in spaced relation in said vapor chamber, terminal conductors for said electrodes, an amount of mercury in said vapor chamber, a heater element connected to said conductors to vaporize said mercury at the operating temperature of the device to initiate a discharge between said electrodes and a filament in said gas chamber and in series with said electrodes during the discharge.
20. An electric discharge device comprising a sealed container including two communicating compartments, electrodes disposed in spaced relation and a light source of tungsten operating at incandescence in one compartment, cooperating electrode terminal conductors for said electrodes, a quantity of mercury sufficient in amount to provide mercury vapor about said electrodes at the operating temperature of the lamp and at a pressure high enough to give a discharge between the electrodes and a filament in the other compartment for stabilizing said discharge and operating in an atmosphere of inert gas, means between said compartments whereby communication is provided through a restricted passage.
25. An electric discharge device comprising a sealed container including two communicating compartments, electrodes disposed in spaced relation and a light source of tungsten operating at incandescence in one compartment, cooperating electrode terminal conductors for said electrodes, a quantity of mercury sufficient in amount to provide mercury vapor about said electrodes at the operating temperature of the lamp and at a pressure high enough to give a discharge between the electrodes and a filament in the other compartment for stabilizing said discharge and operating in an atmosphere of inert gas, means between said compartments whereby communication is provided through a restricted passage.
30. An electric discharge device comprising a sealed container including two communicating compartments, electrodes disposed in spaced relation and a light source of tungsten operating at incandescence in one compartment, cooperating electrode terminal conductors for said electrodes, a quantity of mercury sufficient in amount to provide mercury vapor about said electrodes at the operating temperature of the lamp and at a pressure high enough to give a discharge between the electrodes and a filament in the other compartment for stabilizing said discharge and operating in an atmosphere of inert gas, means between said compartments whereby communication is provided through a restricted passage.
35. An electric discharge device comprising a sealed container including two communicating compartments, electrodes disposed in spaced relation and a light source of tungsten operating at incandescence in one compartment, cooperating electrode terminal conductors for said electrodes, a quantity of mercury sufficient in amount to provide mercury vapor about said electrodes at the operating temperature of the lamp and at a pressure high enough to give a discharge between the electrodes and a filament in the other compartment for stabilizing said discharge and operating in an atmosphere of inert gas, means between said compartments whereby communication is provided through a restricted passage.
40. An electric discharge device comprising a sealed container including two communicating compartments, electrodes disposed in spaced relation and a light source of tungsten operating at incandescence in one compartment, cooperating electrode terminal conductors for said electrodes, a quantity of mercury sufficient in amount to provide mercury vapor about said electrodes at the operating temperature of the lamp and at a pressure high enough to give a discharge between the electrodes and a filament in the other compartment for stabilizing said discharge and operating in an atmosphere of inert gas, means between said compartments whereby communication is provided through a restricted passage.

JOHN W. MARDEN. 40
